COMBINED BASKETBALL GOAL AND BRACKET

William C. Toedter, 1034 Nela Parkway,
Toledo, Ohio 43615

Filed Sept. 27, 1973, Ser. No. 401,352

Term of patent 14 years

Int. Cl. D21—02

U.S. Cl. D34—5 VV

FIG. 1

FIG. 2

FIG. 3

FIG. 4

FIG. 7

FIG. 6

FIG. 5

FIG. 1 is a perspective view of a combined basketball goal and bracket;

FIG. 2 is a top view of the combined basketball goal and bracket;

FIG. 3 is a rear view of the goal and bracket and represents the right side of FIG. 2;

FIG. 4 is a side view of the goal and bracket and represents the top or bottom view of FIG. 2;

FIG. 5 is a sectional view 5—5 of FIG. 2;

FIG. 6 is a sectional view 6—6 of FIG. 2;

FIG. 7 is a sectional view 7—7 of FIG. 2.

In the figures a single net hook is shown for convenience of illustration, it being understood that a hook is present in each opening about the hoop.

1 claim:

The ornamental design for a combined basketball goal and bracket, as shown and described.
